CLAIM

The ornamental design for a display screen with transitional graphical user interface, as shown and described.

DESCRIPTION

FIG. 1 is a front view of a first image in a sequence according to a first embodiment of our design for a display screen with transitional graphical user interface;

FIG. 2 is a front view of a second image in the sequence thereof;

FIG. 3 is a front view of a third image in the sequence thereof;

FIG. 4 is a front view of a first image in a sequence according to a second embodiment of our design for a display screen with transitional graphical user interface;

FIG. 5 is a front view of a second image in the sequence thereof;

FIG. 6 is a front view of a third image in the sequence thereof;

FIG. 7 is a front view of a first image in the sequence of FIGS. 1-3 shown with a different broken line environment; FIG. 8 is a front view of a second image in the sequence thereof; and,

FIG. 9 is a front view of a third image in the sequence thereof.

The appearance of the claimed design transitions between the images shown in FIGS. 1 through 3, between the images shown in FIGS. 4 through 6, and between the images shown in FIGS. 7 through 9, respectively. The process or period in which one image transitions to another forms no part of the claimed design.

The outermost broken line rounded rectangle showing an electronic device illustrates environmental subject matter. The broken line showing a display screen, and all other broken lines showing portions of the graphical user interface

(Continued)

illustrate portions of the article. None of the aforementioned broken line subject matter forms part of the claimed design.

1 Claim, 9 Drawing Sheets
